EFRAIM BARBER, OF HARTFORD, CONNECTICUT.

TIME-ACTUATING DEVICE FOR GAS-COCKS AND THE LIKE.

1,143,933.

Specification of Letters Patent. Patented June 22, 1915.

Application filed August 28, 1912. Serial No. 717,451.

To all whom it may concern:

Be it known that I, EFRAIM BARBER, a subject of the Czar of Russia, and a resident of Hartford, in the county of Hartford and State of Connecticut, have invented a new and Improved Time-Actuating Device for Gas-Cocks and the like, of which the following is a specification.

My invention relates to the class of devices employed more especially for providing or extinguishing light at predetermined times, and an object of my invention, among others, is to provide a device of this class, extremely simple in its construction and one that may be readily used in connection with existing time devices for producing the desired results.

One form of device embodying my invention and in the construction and use of which the objects herein set out, as well as others, may be attained, is illustrated in the accompanying drawings, in which—

Figure 1 is a view in side elevation of a gas fixture showing my improved device forming part thereof. Fig. 2 is a view in section thereof on plane denoted by dotted line 2—2 of Fig. 1. Fig. 3 is a detail view in horizontal section through the device on plane denoted by dotted line 3—3 of Fig. 1, looking upward. Fig. 4 is a like view showing the parts in position for operation.

In the accompanying drawings, the numeral 6 denotes a tube at the end of which a gas fixture 7 is attached, this fixture, in the present case, being a connection embodying a valve casing 8 and a burner tip 9.

The valve body contains the usual valve plug 10 having the port 11 for the passage of gas from the tube 6 to the burner 9.

In carrying out my invention I provide a number of stops, one at least of which is to limit the movement of the valve when it reaches an extreme position (either open or closed) and two at least of which shall limit the movement of the valve when it reaches the opposite extreme position. For example one stop may be employed to limit the movement of the valve when it reaches its closed position and two to limit its movement when it reaches its open position, or one stop may be employed to limit the movement of the valve when it reaches its open position and two to limit its movement when it reaches its closed position. The term "extreme position" is employed to describe the valve when it is either opened or closed, that is,

when the valve is closed it is in one extreme position and when it is open it is in the other extreme position. In the form of device herein shown a number of stops for limiting the movement of the valve when it reaches either of the above mentioned positions are employed, these being in the form of notches in the lower edge of the valve body and consisting of a set of opening notches 12 and a set of shut-off notches 5, each of these sets consisting of two notches located on diametrically opposite sides of the body.

The plug 10 is provided with a thumb piece 13, of any suitable form and construction, and a latch 14 is pivotally mounted on this thumb piece 13, one end of the latch being formed and located in a position to enter the notches 5 or 12. A spring 15 may be employed to hold the latch, so that its end will normally engage the surface of the casing 8 and within the notches 5 or 12, and a holder 16 is constructed to engage the opposite end of the latch to hold it, when desired, with its notch engaging end out of engagement with the outer surface of the casing 8 and so that this end will not engage said stops.

The end of the thumb piece 13 is suitably formed to receive the key 17 of a time piece 18. This time piece may be of any well known form, the key 17 constituting a part of the alarm mechanism of the clock constructed and operating in a manner well known. A support 19 may be employed as an additional means for suspending the clock or time piece 18 in position.

In the operation of the device the alarm mechanism of the clock is wound in the ordinary manner and set to operate at the desired time. The clock is then suspended from the gas fixture, as shown in Fig. 1, and the plug 10 is turned to the position shown in Fig. 4 with the latch 14 just disengaged from one of the notches 12. The turning of the plug to this extent does not materially affect the flow of gas, which is supposed to be lighted. At the required time the alarm mechanism will be operated and, in its turning movement, will rotate the plug 10 from its open position shown in Fig. 4 to its opposite or closed position to shut off the gas, the latch 14 engaging the next succeeding shut-off notch 12 and stopping the rotation of the parts when the plug is in position to shut off the gas.

If it be desired to turn on the gas at a certain time the same operation is followed with the exception that the plug 10 is located a quarter of a turn from the position shown in the drawings and with the latch 14 disengaged, but resting close to the edge of a shut-off notch as hereinbefore explained. A pilot light 20, formed by a tube extending from the gas pipe, is located in proper position with respect to the burner to ignite the gas when it shall be turned on, it, of course, being understood that the pilot light is in operation in the usual manner. The alarm mechanism now being operated at the desired time the plug 10 is given a quarter turn from its closed position to its opposite or open position, and the latch 14 engaging with the next succeeding opening notch stops the operation of the parts with the gas turned on, and the burner, therefore, lighted. The term "position" as employed in the claims herein is intended to designate the condition of the valve and as qualified by the terms "open" and "closed". It will be seen that a gas cock is provided in which the plug may be moved from either of its extreme (open or closed) positions to its opposite (either closed or open) position, by a power driven device rotating the plug always in the same direction. That is, if the plug is in one extreme or open position, the power driven device may be employed to move it in a certain direction and the stop will operate to stop movement when the plug reaches its opposite extreme or closed position, and likewise if the plug is in one extreme or closed position the power driven device may be employed to move it in the same direction as before and the stop will operate to stop movement of the plug when it reaches its other extreme or opposite or open position.

If it shall be desired to operate the device for the purpose of attracting attention, as in the case of illuminated signs or the like, the latch 14 may be engaged with the holder 16, and then, by attachment of a proper device to the thumb piece 13 to rotate it at such speed as may be desired, the gas will be lighted, and then immediately extinguished and then again relighted and so on.

While I have illustrated my invention as applicable to a lighting fixture employing gas as an illuminant, it will be understood that my improvement may be applied to any lighting fixture.

While I have shown and described herein a preferred form of mechanism for accomplishing my purpose, it is not essential that a device shall be constructed precisely as shown herein to contain the invention, and the latter is, therefore, not limited to a device constructed in exact accordance with that herein disclosed.

I claim—

1. A valve actuating device including a valve casing, a valve plug to control the flow of fluid through the casing, means movably mounted upon the plug to stop its movement, means for attachment of a power driven device to rotate the plug always in one direction, a stop located in fixed position to be engaged by said stopping means when the valve is in one position, a stop to be engaged by said stopping means when the valve is rotated in a certain direction to its opposite position, another stop to be engaged by said stopping means when rotation of the valve is continued in the same direction, and means for automatically engaging the stopping means with the stops. 80

2. A valve actuating device including a valve casing, a plug to control the flow of fluid through said casing, means movably attached to the plug to stop its movement, means for attachment of a power driven device to rotate said plug always in one direction, a plural number of stops located on said casing to receive the stopping means when the valve plug is moved continuously in one direction to any of its extreme positions, means for causing said stopping means to automatically engage said stops and means for rotating the plug continuously in one direction. 95

3. A valve actuating device including a valve casing, a plug to control the flow of fluid through said casing, a device for actuating said plug and including means for attachment of a time piece to rotate the plug always in one direction, means movably mounted on the actuating device to stop movement of the plug, a plural number of stops located in fixed position to receive said stopping means when the valve is moved in one direction to either of its extreme positions, and means for influencing the stopping means to normally engage said stops. 100

4. A valve actuating device including a valve casing, a plug to control the flow of fluid through said casing, a burner attached to the valve, means for igniting the fluid, a device for rotating the plug always in one direction and including means for attachment of a time device to effect such rotation, stopping means movably mounted on the plug, a plural number of stops located to stop movement of the valve when rotated in one direction to any of its extreme positions, and means for influencing the stopping means to normally engage said stops. 115

5. A valve actuating device including a valve casing, a plug to control the flow of fluid through said casing, means movably attached to the plug to stop its movement, means for causing said stopping means to normally engage hereinafter mentioned stops, a plural number of stops to position 130

- the valve for one operation and a single stop to position the valve for the other operation, and means for rotating the plug always in one direction and including means for attachment of a power driven device to effect such rotation.
6. A valve actuating device including a valve casing, a valve plug to control the flow of fluid through the casing, stopping means carried by said plug and movable thereon, a stop located in fixed position to be engaged by said stopping means when the valve is closed, a stop to be engaged by said stopping means when the valve is moved to its open position, another stop to be engaged by said stopping means when the valve is moved in the same direction to its closed position, means for normally engaging the stopping means with the stops, and means for operating the plug and including means for attachment of a power driven device to rotate said plug always in the same direction.
7. A valve actuating device including a valve casing, a valve plug to control the flow of fluid through the casing, means for attachment of a power driven device to rotate said plug always in one direction, stop-

ping means carried by said plug and movable thereon, a stop located in fixed position to be engaged by said stopping means when the valve is in one extreme position, and a plural number of stops located in fixed position to be engaged by said stopping means when the valve is moved in one direction to any of its other extreme positions.

8. A valve actuating device including a valve casing, a valve plug to control the flow of fluid through said casing and mounted for complete rotation therein, means for attachment of a power driven device to rotate said plug always in one direction, stopping means carried by said plug and movable thereon, a plural number of stops located in fixed position to be engaged by said stopping means when the valve is rotated in a single direction to a plural number of extreme positions, a stop being provided for each of said positions, and means for normally engaging the stopping means with the stops.

EFRAIM BARBER.
